Attorney

UNITED STATES PATENT OFFICE

JOHN E. STEINOUR, OF LOS ANGELES, CALIFORNIA

SHARPENING TOOL

Application filed November 21, 1929. Serial No. 408,877.

This invention relates to a sharpening tool and has relation more particularly to a device of this kind especially designed and adapted for use with the spiral cutting blades of lawn mowers.

It is an object of the invention to provide a device of this kind adapted to have used in connection therewith a file or kindred grinding element and wherein the device is provided with means to maintain the grinding element in effective position at all times with respect to the mower blade being sharpened.

The invention consists in the details of construction and in the combination and arrangement of the several parts of my improved sharpening tool whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in top plan of a sharpening tool constructed in accordance with an embodiment of my invention and in applied position, an associated grinding member and spiral blade being shown in fragment, the applied file being indicated by broken lines;

Figure 2 is a sectional view taken substantially on the line 2—2 of Figure 1 with the applied file indicated by broken lines;

Figure 3 is a sectional view taken substantially on the line 3—3 of Figure 2.

As disclosed in the accompanying drawings, my improved tool comprises an elongated plate P of desired dimensions and which has an intermediate portion cut out to provide an elongated and relatively wide opening 1. The resultant side members 2 defining the opening 1 are upwardly offset substantially from end to end to a position slightly above the adjacent face of the plate P proper. The inner marginal portions of the side members 2 at points spaced lengthwise thereof are provided with the downwardly disposed short arms 3 of a length to

extend a slight distance beyond the opposite or under face of the plate P proper, the extremities of said arms 3 being continued by the inwardly disposed arms 4. These arms 4 are each substantially in the form of a V with its apex outwardly disposed and the arms 4 at one side of the plate P are so arranged with the arms 4 at the opposite side thereof to provide a plurality of crossed guideways for selective engagement with the spiral blade B of a lawn mower.

One end portion of the plate P has struck therefrom the downwardly disposed ears or clips 5 which are adapted to straddle a guide member 6.

In the present embodiment of my invention the guide member 6 is the conventional rod comprised in lawn mower structures connecting the wheel housings and which rod is disposed in parallelism with the axis of the rotating cutter.

In practice, my improved tool is engaged through the medium of the ears or clips 4 with the guide member 6 with the blade B to be sharpened disposed between the selected arms 4. A file or kindred grinding element is placed upon the tool whereupon the tool together with the applied grinding member is moved lengthwise of the guide member 6 resulting in the desired sharpening of the cutting edge of the blade B, it being understood that as the tool is reciprocated back and forth upon the guide member 6 the blade B will rock back and forth, thus assuring a most effective cutting edge for the blade.

By providing a plurality of longitudinally spaced arms 4 a single tool can be conveniently employed with different size lawn mowers and more particularly to compensate for different relative spacings between the guide member 6 and the rotating cutting member.

While I have hereinbefore particularly referred to the rod 6 connecting the wheel housings as the guide member, yet it is to be understood that the axle of the mower may be employed for the same purpose.

The opposite end portions of the plate P are formed to provide hand grasps 7 to facilitate the desired manipulation of the tool.

The extremities of the side members 2 are provided with the inwardly disposed lugs 8 which engage over the applied file to effectively maintain the file in desired working position. As clearly illustrated in the accompanying drawings, the arms 5 have their free end portions offset beyond one face of the side members 2 while the free end portions of the lugs 8 are offset beyond the opposite faces of said members 2.

It is also believed to be apparent that by provision of the arms 5 as herein described and illustrated my improved tool can be employed with equal facility with either a right or left hand mower.

From the foregoing description it is thought to be obvious that a sharpening tool constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. A device of the class described and in combination comprising a plate having an intermediate opening and offset side members defining said opening, guiding means carried by the plate, blade engaging fingers carried by the plate at opposite sides of the opening therein and extending inwardly of said opening, and a sharpening element supported by the plate between the side members.

2. A device of the class described and in combination comprising a plate having an intermediate opening and offset side members defining said opening, guiding means carried by the plate, blade engaging fingers carried by the plate at opposite sides of the opening therein and extending inwardly of said opening, the inwardly disposed fingers having their free end portions positioned to one side of the plate, and a sharpening element supported by the plate between the side members.

3. A device of the class described and in combination comprising a plate having an intermediate opening and offset side members defining said opening, guiding means carried by the plate, blade engaging fingers carried by the plate at opposite sides of the opening therein and extending inwardly of said opening, the portions of the plate defining the opposite sides of the opening therein being arranged beyond a face of the opening, and a sharpening element supported by the plate between the side members.

4. A device of the class described and in combination comprising a plate having an intermediate opening and offset side members defining said opening, guiding means carried by the plate, blade engaging fingers carried by the plate at opposite sides of the opening therein and extending inwardly of said opening, the portions of the plate defining the sides of the opening being arranged beyond one face of the plate, the free ends of the fingers being positioned beyond the opposite side of the plate, and a sharpening element supported by the plate between the side members.

5. A device of the character described and in combination, an elongated plate having an intermediate opening and offset side members defining said opening, guiding means carried by the plate adjacent one end thereof, fingers carried by the offset side members and extending inwardly of the opening, said fingers being adapted to engage therebetween a cutter blade whereby to hold the blade in adjusted position, a sharpening element supported by the plate between the side members, and means for retaining the sharpening element on the plate.

In testimony whereof I hereunto affix my signature.
